UNITED STATES PATENT OFFICE.

XAVER BRÜGGER, OF HORGEN, ZURICH, SWITZERLAND.

SKEIN HOLDER FOR THREAD-SPOOLING MACHINES.

Application filed December 18, 1926, Serial No. 155,715, and in Switzerland June 26, 1926.

Reeling and winding machines are known wherein a plurality of reels or the like are mounted between the arms of spider frames whereby they can be brought successively 5 into and out of operative position, the object being to enable one reel to be prepared while another one is in operation.

The present invention relates to a device of this kind for use as a skein holder for 10 thread spooling machines, and the invention consists essentially in mounting the spider frames by means of hubs on a shaft having longitudinal, equidistant grooves, the hubs being provided with spring-pressed balls 15 adapted to engage in said grooves for retaining the frames with different reels in operative position.

The frames are moreover provided for each reel with a known form of thread tensioning device composed of a U-frame arranged so as to swing about the axis of a reel, the frame being according to the invention fitted with a thread guide and with an adjustable weight whereby the tension can 25 be regulated.

Fig. 1 of the accompanying drawings represents a side view of an arrangement according to the invention,

Fig. 2, a front view showing merely the 30 reels which are in operative position,

Fig. 3, a rear view of the arrangement,

Fig. 4, a side and a top view of the spider frame, and

Fig. 5, a view of a thread guide employed in the arrangement.

A supporting frame 1 carries rigidly a horizontal shaft 2 on which one or more reel holders are arranged so that they can be adjusted thereon longitudinally and rotatively. 40 In the construction shown, each reel holder is composed of a hub 6 to which three pairs of radial, equidistant arms 11, 12 and 13 are connected so as to form a spider frame. Between the free ends of each pair of arms, at 45 14, 15 and 16 respectively, a reel is mounted so that it can be turned by means of the holder into and out of operative position. Fig. 1 shows one reel 19 in operative position over the spooling device 25, while two 50 reels 17 and 18 are held at the back of the machine where they can be fitted up with skeins or hanks so as to be ready for the spooling operation as soon as the reel 19 is empty.

55 To secure the holder with either reel in operative position, the shaft 2 is provided

with three equidistant, preferably semi-cylindrical, longitudinal grooves 3, 4 and 5 carried through the whole length of the shaft. The hub has a drilled stub in which there is 60 a ball 8 a spring 9, and behind the latter an adjusting screw 10. The spring bears against the ball and causes it to snap into the grooves of the shaft for retaining the reel holder in its different positions. The 65 screw 10 is adjustable so that the spring pressure, while sufficient for retaining the holder, allows the latter to be turned from one position to the other. The holder or holders can also be moved to any suitable 70 position along the shaft.

For maintaining the thread 24 in uniform tension on its travel from the reel to the spool 25, a U-frame 21 is hinged at 20 to each pair of arms. A thread guide in the 75 form of a rod 23 is arranged along the transverse member of the frame 21 and connected thereto at one end only so that the thread can be easily slipped in between the rod and the frame member. The frame 21 80 tends to hang perpendicularly from the suspending point and is deflected more or less from this position by the thread 24 which will therefore be kept in regular tension. To regulate the tension, a weight 22 is 85 arranged on one of the radial frame members so that it can be adjusted thereon according to requirements.

The frame 1 may either form part of the spooling machine or constitute a separate 90 structure.

I claim:

1. A skein holder for thread spooling machines comprising a horizontal shaft having equidistant longitudinal grooves, a support 95 to which said shaft is rigidly connected, frames comprising pairs of radial arms connected to a hub and loosely mounted on said shaft by means of the hub, a reel mounted between each pair of arms, and a spring-pressed ball held in the hub so as to engage in the grooves of the shaft for holding any particular reel in operative position.

2. The structure claimed in claim 1 in combination with a U-frame connected 105 hingedly to the ends of each pair of arms, a thread guide at the free end of said U-frame, and a weight arranged adjustably on said U-frame.

XAVER BRÜGGER.
